US00D794615S

(12) **United States Design Patent** (10) **Patent No.:** **US D794,615 S**
(45) **Date of Patent:** **** Aug. 15, 2017**

(54) **SINGLE FIN ANTENNA**

- (71) Applicant: **TAOGLAS GROUP HOLDINGS**, Enniscorthy, County Wexford (IE)
- (72) Inventors: **Ronan Quinlan**, Dublin (IE); **Dermot O'Shea**, La Jolla, CA (US)
- (73) Assignee: **TAOGLAS GROUP HOLDINGS**, Enniscorthy (IE)
- (**) Term: **15 Years**

(21) Appl. No.: **29/540,616**

(22) Filed: **Sep. 25, 2015**

(51) LOC (10) Cl. **14-03**
(52) U.S. Cl. **USPC** **D14/230**

(58) **Field of Classification Search**

(57) **CLAIM**

The ornamental design for a single fin antenna, as shown and described.

DESCRIPTION

FIG. 1 is a perspective view of a single fin antenna;
FIG. 2 is a right side view of a single fin antenna;
FIG. 3 is a left side view of a single fin antenna;
FIG. 4 is a front view of a single fin antenna;
FIG. 5 is a back view of a single fin antenna;
FIG. 6 is a top view of a single fin antenna; and,
FIG. 7 is a bottom view of a single fin antenna.
The broken lines are included for illustrative purposes only
and form no part of the claimed design.

1 Claim, 7 Drawing Sheets
